UNITED STATES PATENT OFFICE.

ABBOTT L. JOHNSON, OF MUNCIE, INDIANA.

DESIGN FOR A RAILWAY BULLETIN-BOARD.

SPECIFICATION forming part of Design No. 23,918, dated December 25, 1894.

Application filed October 23, 1894. Serial No. 526,764. Term of patent 14 years.

To all whom it may concern:

Be it known that I, ABBOTT L. JOHNSON, a citizen of the United States, residing at Muncie, in the county of Delaware and State of Indiana, have invented and produced a new and original Design for a Railway Bulletin-Board, of which the following is a specification, reference being had to the accompanying drawing, which shows my design by a view 10 in front elevation.

The leading feature of my design consists in the bulletin-board provided with the ornamental scroll-work on the top.

A is the bulletin-board proper, of rectangular outline and flanked by lateral extensions B, B, in imitation of panels to represent vertical tiers of rectangular compartments at opposite ends of the board.

C is the ornamental scroll-work having its 20 central portion formed in two peripherally contacting approximate circles C' and C²,

with scroll-work junctions at q and p and each crossed by diagonal bars r, inclining in opposite directions in the respective circles. In the cross-bars r of the circular part C² is 25 formed the intersecting capital letter "N;" and in those of the companion-part C' is formed the intersecting capital letter "B." At the outer sides of the central circular parts of the ornamental top C, they merge 30 into scroll-work C³, C⁴ which joins with that proceeding outward from the base-junction p, and is continued obliquely downward to the ends of the bulletin-board.

What I claim is—

The design for a railway bulletin-board substantially as herein shown and described.

ABBOTT L. JOHNSON.

In presence of—

M. J. FROST,
J. W. DYRENFORTH.
